FIG. 1

FIG. 2

FIG. 3

FIG. 5

Fig. 1 is a top plan view of the fruit-packing tray, showing our new design, a major portion of the tray being shown in phantom lines to indicate repetition of the design;

Fig. 2 is an enlarged, fragmentary top plan view of the fruit-packing tray shown in Fig. 1;

Fig. 3 is a side elevational view of the fruit-packing tray shown in Fig. 1;

Fig. 4 is an end elevational view of the fruit-packing tray shown in Fig. 1; and

Fig. 5 is an enlarged fragmentary view in perspective of one corner portion of the fruit-packing tray as viewed from the upper left or lower right in Fig. 1.

We claim:

The ornamental design for a fruit-packing tray, substantially as shown.
